US00D878325S

(12) **United States Design Patent** (10) **Patent No.:** **US D878,325 S**
(45) **Date of Patent:** **** Mar. 17, 2020**

(54) **ELECTRONIC INPUT DEVICE**

(71) Applicant: **Amazon Technologies, Inc.**, Seattle, WA (US)

(72) Inventors: **Michael Edward James Paterson**, San Francisco, CA (US); **Giles David Matthew McWilliam**, San Francisco, CA (US); **Marc Rene Walliser**, San Francisco, CA (US)

(73) Assignee: **Amazon Technologies, Inc.**, Seattle, WA (US)

(**) Term: **15 Years**

(21) Appl. No.: **29/644,671**

(22) Filed: **Apr. 19, 2018**

(51) LOC (12) Cl. **14-03**

(52) U.S. Cl.

USPC **D14/203.1**; D14/496; D14/228; D14/357

(58) **Field of Classification Search**

USPC D14/240, 242, 358, 351, 356, 357, 125, D14/155, 162, 167, 168, 172, 175, 188, D14/195, 203.1, 203.6, 203.8, 204, 209.1, D14/216, 217, 218, 228, 299, 496, 140, D14/142, 388, 238.1; D13/123, 124, 152, D13/158, 162, 162.1, 168, 173, 184, 199

CPC . G06F 3/16; G06F 3/162; G06F 3/165; G06F 3/167; G10L 15/07

(57) **CLAIM**

The ornamental design for an electronic input device, as shown and described.

DESCRIPTION

FIG. 1 is a front perspective view of a first embodiment of an electronic input device;

FIG. 2 is a back perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof;

FIG. 9 is a front perspective view of a second embodiment of an electronic input device;

FIG. 10 is a back perspective view thereof;

FIG. 11 is a front view thereof;

FIG. 12 is a back view thereof;

FIG. 13 is a left-side view thereof;

FIG. 14 is a right-side view thereof;

FIG. 15 is a top view thereof; and,

FIG. 16 is a bottom view thereof.

The broken lines depict portions of the electronic input device that form no part of the claimed design.

1 Claim, 16 Drawing Sheets
